UNITED STATES PATENT OFFICE.

MAURICE HERBERT COWAN, OF BROOKLYN, NEW YORK.

WATER-HEATER.

1,338,447.

Specification of Letters Patent. Patented Apr. 27, 1920.

Application filed February 15, 1919. Serial No. 277,138.

To all whom it may concern:

Be it known that I, MAURICE HERBERT COWAN, a citizen of the United States, residing in the borough of Brooklyn, county 5 of Kings, and State of New York, have invented a certain new and useful Water-Heater, of which the following is a specification.

This invention is a water heater, intended 10 for use of gas as a heating medium, and the device of the present invention is so constructed that it may be either associated with a gas range or may be used independently as a separate unit.

15 The object of the present invention is to provide a heater of the type specified which will possess maximum efficiency for fuel consumption, and this object is attained through a novel disposition of conduit pipes or tubes 20 and the manner of applying heat thereto. The heater of this invention is adapted to be associated with a hot water boiler or reservoir properly connected thereto in such manner that the water contained in the 25 boiler fills the entire system. The water in the boiler is heated to the desired temperature through the heating of the water in the pipes or tubes referred to, and, as the water in said pipes is heated, it flows to the 30 boiler after well known principles of thermo-siphon circulation.

35 Features of the invention other than those specified will be apparent from the herein-after detailed description taken in conjunction with the accompanying drawings.

In the accompanying drawings I have illustrated different practical embodiments of the invention, but the constructions shown therein are to be understood as illustrative 40 only, and not as defining the limits of the invention.

Figure 1 is a perspective view of a well known type of kitchen gas range with which is associated a heater embodying the present invention;

Fig. 2 is a perspective view showing a slightly modified form of heater adapted for use entirely independent of a range or any other form of heating or cooking means;

50 Fig. 3 is a section in the plane of the line 3-3 of Fig. 4, showing the coils within the heater in full elevation, the device as shown in Fig. 3 being that form of the invention illustrated in Fig. 1;

Fig. 4 is a section on the line 4-4 of 55 Fig. 3;

Fig. 5 is a section on the line 5-5 of Fig. 2;

Fig. 6 is a section on the line 6-6 of Fig. 5. 60

Figs. 7 and 8 are detail views of differently shaped pipe coils which may be employed in the carrying out of the present invention.

Referring to the drawings, and more particularly, Figs. 1, 3, 4 and 7, A designates an oblong cast iron or sheet metal casing, preferably made of such size that it may be readily mounted by means of ears a on the end of any well known form of gas range 70 B, after the manner shown in Fig. 1. The casing A is preferably provided at one side with a door a', through which access may be had to the interior of the casing. The door may be of any size desired, but is preferably made quite large to allow of ready access to all parts of the interior of the casing, whereby the same may be cleansed from time to time as occasion may require. 75

The top and sides of the casing are normally closed and the bottom is normally sealed by means of a plate C, as shown in Fig. 3. The top of the casing is, however, preferably perforated as at c, to allow spent heat and gases free exit from the interior of 85 the casing, while the lateral wall of said casing is provided with a plurality of apertures c' through which sufficient air to properly support combustion may enter.

Positioned in the lower portion of the 90 casing and preferably supported on lugs d, extending inwardly from the walls of plate C, is a gas burner D, here shown in substantially the form of a double loop. Gas is fed in the said burner from a main or head E, 95 through two valve control connections e as shown best in Fig. 3, each connection feeding into one of the looped portions of the burner. Both portions of the burner are connected to one another interiorly so that each connection e feed both loops of the burner. If only a relatively small quantity of heat is desired, one of the connections may be employed, but if maximum heat is wanted both connections may be opened. 100 The gas flows from the burner through the perforations d' formed therein and burns immediately exteriorly thereof. 105

The introduction of heat into the casing in the manner described is for the purpose of heating water to a desired temperature, and this water is subjected to the heating influence of the burner, by passing the liquid through a series of coils of a particular shape intended to heat the water to the highest degree of efficiency for fuel consumption.

10 In the preferred embodiment of the invention, a relatively large body of water is maintained in a reservoir which may be a boiler F, of any of the well known and commonly used commercial forms. Leading 15 from the lower end of the boiler to a series of coils interiorly of the casing A is a feed pipe connection f, while from the casing a return pipe connection f' leads the water back to the boiler. A closed circuit is thus 20 provided through which the water circulates in accordance with well known hydrostatic principles due to the heating of the water in the coils interiorly of the casing.

The heating coils which have been referred to as positioned interiorly of the casing A form an important part of the present invention. It is of course well known that coils positioned within a casing and heated by gas flame have long been employed, but in every case the disposition of the coils were such that the efficiency of heating for fuel consumption was very low. This was due largely to the hit or miss practice of displacement of the pipes or tubes within the heating chamber, and this inefficient method of displacement, as well as the forming of the coils, necessitated the production of a large quantity of heat which escaped from the casing as waste fuel consumption without having even been brought to impinge upon the tubes.

For example, in many of the well known forms of gas water heater, the coils are in the form of a helix and are heated by a circular burner positioned immediately below and in the axis of the helix. In such construction, the major portion of the heat generated by the burner flows unobstructedly up through the center of the helix and upwardly through the space between the helix and the casing, entirely free from contact with the coils which it is supposed to heat. Accordingly, the heat wastage was large, only a relatively small portion of the fuel consumed functioning to heat the tubes. With the foregoing in mind, and after prolonged experimentation, the coil displacement illustrated in the accompanying drawings was evolved, and, in practice, shows a big increase of efficiency over any of the constructions well known and now employed.

In accordance with this construction, the intake or feeder pipe f branches interiorly 65 of the casing A and immediately above the

burner D into two or more tubes which are preferably copper or of some other suitable material having a high conductivity coefficient. The two branch pipes h and h' are formed to a large number of coils G and G' 70 of the respective tubes which extend upwardly to the top of the casing and connect with the common outlet pipe f'. These coils may differ slightly in shape within the limits of this invention, but the preferred form 75 of coil employed is of the figure 8-shape as clearly shown in the drawings. The coils are preferably made of such size that they substantially fill the cross sectional confines of the casing and a large number of coils 80 are formed in each tube. There is therefore what may be termed a plurality of series of coils, the coils of each pipe forming one series entirely independent of the coils of the other pipe which form the other series. 85 The coils are, moreover, preferably so disposed that the coils of one series are alternately interspaced with those of the other series, so that a very compact construction results in spite of the large quantity of 90 tubing employed. The advantage of this construction is that the cross sectional area of the casing is substantially filled with, figuratively speaking, interlaced tubing so that the heat emanating from the burner D 95 cannot pass unobstructedly upward past the coils, but is forced to impinge said coils and perform the intended function of heating the same. In practice, the heat circulates upwardly between the coils heating 100 each coil equally throughout. The coils are preferably subjected to the heat and the maximum of the burner efficiency is secured.

In a slightly modified construction, illustrated in Figs. 2, 5 and 6, the casing A' is 105 provided with legs i so that the casing may stand by itself and independent of any other means of support. The casing is however preferably connected up in a pipe circuit with a boiler after the general method shown 110 in Fig. 1 and the construction is in many respects, to the preferred embodiment hereinbefore described. However, as shown in Fig. 5, the burner D', although mounted in the lower portion of the casing is inclined 115 so as to give it greater length and consequent greater heating capacity. With this positioning of the burner, the coils G² and G³, in order that they be made to substantially fill the chamber, above the burner, are 120 graduated in size from the bottom to the top of the casing. The advantage of the construction shown in Fig. 5 is that the greater portion of the coils, from the bottom up, are subjected directly to the action of the flame. 125 However, both of the foregoing constructions, the principle underlying in the present invention is the same, since the coils are substantially coextensive with the cross sectional area of that portion of the casing 130

above the burner whereby heat arising from the burner is forced to impinge the coils, circulate between them and properly heat the same to a high degree of efficiency.

5 In Fig. 8 a modified form of coil is shown which may be employed, but, although this modified construction of coil will heat the water to a fair degree of efficiency, due more particularly to other features of the invention, the form of coil shown in the remaining figures and specifically in Fig. 7 is preferred, and as this latter form is conducive to the best results.

10 In gas heaters constructed in accordance with either of the foregoing embodiments of this invention, function in accordance with the same well known principles of the thermo-siphon system in the heating and circulating of water through a closed circuit having therein a reservoir of the common kitchen boiler type. While the embodiment of the boiler and system is preferable to maintain a head or reservoir supply of water in a heated condition, which may be 15 drawn off, from time to time, in greater or lesser quantities as desired, it is practical to use the heater to the exclusion of the boiler,

making a direct connection from the feed water pipe, through the heating coil and thence to a tap.

20 Having thus fully described the invention, what I claim as new, and desire to secure by Letters Patent is:

A water heater embodying an upstanding casing, a gas burner extending transversely 35 of the casing and inclined upwardly in a diagonal direction interiorly of the casing, a water inlet and a water outlet, one at the top and one at the bottom of the casing, and a plurality of tubes connecting said water 40 inlet and outlet, said tubes being formed into superimposed alternately interposed figure-8 shaped loops of progressively greater dimensions from the lower portion of the casing upwardly to a point above the uppermost 45 portion of the burner, while the remaining superimposed loops are of substantially the same dimensions one to another, whereby maximum heat may be supplied to maximum radiating surface of the tubes in a relatively 50 small and compact heater.

In testimony whereof I have signed my name to this specification.

MAURICE HERBERT COWAN.
